(57) **CLAIM**

I claim the ornamental design for a secure cell phone holder, as shown and described.

DESCRIPTION

FIG. 1 is a perspective view of the claimed design.

FIG. 2 is a front elevation view thereof.

FIG. 3 is a back elevation view thereof.

FIG. 4 is a left-side elevation view thereof.

FIG. 5 is a ride-side elevation view thereof.

FIG. 6 is a top plan view thereof.

FIG. 7 is a bottom plan view thereof; and,

FIG. 8 is a perspective view of the secure cell phone holder worn on the waist of a user.

The broken line drawing of a user shown in FIG. 8 shows environmental use of the claimed design only and forms no part of the claimed design.
